(57) **CLAIM**

The ornamental design for an electronic device, as shown and described.

DESCRIPTION

FIG. 1 is a perspective view of an electronic device showing our new design;

FIG. 2 is another perspective view thereof;

FIG. 3 is a front view thereof;

FIG. 4 is a rear view thereof;

FIG. 5 is a right side view thereof;

FIG. 6 is a left side view thereof;

(Continued)

FIG. 7 is a top view thereof; and,
FIG. 8 is a bottomview thereof.

The dashed broken lines illustrate structure or features which form no part of the claimed design.
The oblique shade lines illustrate a reflective or glossy surface.

1 Claim, 6 Drawing Sheets
